LEVEL

Hugh A. Chapman, Rte. 4, Gate City, Va.

Filed July 14, 1961, Ser. No. 65,924

Term of patent 14 years

(Cl. D52—6)

The undisclosed bottom of the level is substantially the same in appearance as the top therefor, and the rear is substantially the same as the front.

I claim:

The ornamental design for a level, as shown and described.
